(57) CLAIM

The ornamental design for a cable organizer, as shown and described.

DESCRIPTION

FIG. 1 is a top-front-right perspective view of a cable organizer in accordance with the design;

FIG. 2 is a front side view of a cable organizer in accordance with the design;

FIG. 3 is a back side view of a cable organizer in accordance with the design, the left side view and right side view being identical;

FIG. 4 is a top plain view of a cable organizer in accordance with the design;

FIG. 5 is a bottom plain view of a cable organizer in accordance with the design; and,

FIG. 6 is a top-front-right, cut-away, perspective view showing the interior of a cable organizer in accordance with the design.

The broken lines shown in the drawings represent unclaimed portions of the design and form no part thereof.
